PAPER SEAT-COVERING DISTRIBUTING DEVICE FOR HYGIENIC PANS

Romeo Bacci, Milan, Italy

Application November 8, 1950, Serial No. 194,613

Claims priority, application Italy September 29, 1950

3 Claims. (Cl. 4—243)

The present invention relates to a device for distributing seat-covering sheets for hygienic bowls, and has for its object the elimination of certain objections which are present today in the use of bowls from the sanitary standpoint.

A further object of this invention is to provide a device disposed in a convenient and suitable position for the distribution of a pack of seat-covering sheets in such a manner that the sheets may be applied successively to the bowl seat.

The device of the present invention is characterized by a seat cover of double wall construction for containing a pack of overlapped sanitary sheets adapted for covering the bowl seat at the moment of use; and a forwarding roller, bearing on the lower brim of the sheets to be forwarded, said roller being actuatable at one end by a driving part mounted outside the cover.

The appended drawing shows, but not as a limiting example, an embodiment of the present invention.

Fig. 1 is a side view of the present invention applied to a conventional bowl, the double bottomed cover being turned in its uplifted position.

Fig. 2 is a plan view of a seat-covering sheet being drawn out from the cover.

Fig. 3 is a front view of a seat cover of the present invention and wherein, to achieve greater clearness, the closing wall of the cover itself is assumed as being removed.

Fig. 4 is a transverse axial section on an enlarged scale of the cover illustrated in Fig. 3.

Fig. 5 is a section along the line A—B of the seat-covering pack illustrated in Figs. 3 and 4.

Figs. 1 through 5 show clearly that the cover 1 of the seat 2 of bowl 3 is an openable double walled cover, that is to say, cover 1 is made up of closure wall 53 and a body wall 52 hinged together at 54. Interiorly of the body 52 two supporting ears 55 receive the axle 56 of a roller 57, which roller controls the exit of the seat-coverings. In turn, the cover 52—53 is hinged at 58 to the conventional seat of the bowl, or to a suitable element attached to the bowl. The axle 56 of roller 57 passes out of one end of the side walls of body 52 and terminates in a control knob 59, which is hand-operated.

The pack 60 of thin paper seat-coverings includes a pasteboard 61 on which the sheets 60 bear. This board 61 is provided with two holes 62 through which extend suitable pins or holder 63 attached to the body 52 of the cover. On sheets 60 may be applied another sheet 64 of light pasteboard or heavy paper. Characteristic of pack 60 is the band 65 of strong paper or the like, a portion of which passes through and is disposed between the pack of seat-coverings 60 and board 61, as an effect of the cut 66, and a portion of which band 65 rests on the leaves 67 of sheets 60, which leaves result as an effect of cut 66. This band 65, which may have a size more reduced than that illustrated in the drawing, assures that said leaves 67 stay perfectly taut and in place while the seat-coverings are in body 52, as well as during the exit operation of said

2

coverings. In this manner, the need of using springs is eliminated. Such springs always entail a cost increase and complication in the packaging of said sheet packs. The band 65, besides making more simple the preparation of the sheet pack itself, gives a major guarantee that the said portions 67 of the sheets 60 will not fall and wrinkle before or during their exit operation.

Normally, box 1 will be loaded with 100 sheets to the pack. The loading of the pack is carried out by opening the closure wall 53 of the cover 1, as by moving it about the hinge 54, and then positioning the sheets carried between the boards 61—64 in the body 52 with the free end of the first sheet in engagement with roller 57. The other end of the sheets engages the pins or holders 63. It will, of course, be obvious that to substitute a new pack of sheets for an exhausted one, the above operations will be carried out after removing the boards 61—64 of the exhausted pack.

The control system for the exit of seat-coverings out of opening 71 is simple in that the forwarding roller 57 is borne by fixed holders. The necessary adherence through a slight pressure between roller 57 and the sheets of pack 60 is secured by a spring foil 68 attached at 69 to the wall 52 on which bears the pasteboard 61 of pack 60. Springs 70 are mounted underneath the free end of foil 68 to urge, through due pressure, the sheet pack 60 against the roller 57.

In order to remove each sheet from the box 1, without it being rent or torn, it is necessary that the sheet be in one piece. That is the center of the sheet must not have been removed, although it may have the cut 66 previously described. It is, therefore, a feature of the invention to provide each sheet with a central perforation 21 of a form, preferably oval, to correspond to the central opening in seat 2. This perforation facilitates removal of the central part of the seat cover.

In operation of the aforesaid device, after placing the seat-covering pack 60 into the cover 52—53 and closing the same, use of the device is achieved by rotating the knob 59, whereby roller 57 will also rotate and, because it has a surface adapted to allow a fair adherence, it will frictionally move said seat-covering 60 out through the slit 71 to dispose itself on the seat below.

This process may be repeated in the same manner each time a seat-covering is needed and the device will operate perfectly until exhaustion of the full pack 60.

The dimensions, the materials constituting the various members and the constructional details of said members may vary, as is well understood. However, such variations should and are intended to be comprehended within the meaning and range of equivalence of the present invention.

The device may be combined with a slot machine which locks the axle of the control knob until a suitable coin frees it for supplying a sheet.

What I claim is:

1. In a device of the class described comprising a bowl and a seat hinged to said bowl, the combination of a cover hinged with respect to said seat and said bowl, said cover being adapted to overlie said seat and being movable to a substantially upright position with respect to said seat, said cover comprising a body for reception of a plurality of seat-covers to be employed successively on said seat, a closing wall for closing said cover body, said closing wall being disposed between said seat and said cover body and remaining closed with respect to said cover body during dispensing of said seat-covers, and enclosing said seat-covers in said body, said body having an exit opening for said seat-covers adjacent its hinged connection with respect to said seat, means supporting said seat-covers in said body, said means comprising a pair of pasteboards

confining said seat covers therebetween and of substantially the dimensions of the seat-covers, with one of said pasteboards of slightly less length than the seat-covers whereby said forwarding means may contact the first sheet of the plurality of seat-covers, said seat-covers having a perforate central portion to facilitate removal thereof and a through cut along a portion of said perforate portion, means extending through said cut and bearing on said central portion to hold and guide the same during exit of said seat-covers from said cover-body, forwarding means successively engageable with said seat-covers, said forward means being operable in the said upright position of said cover to deliver said seat-covers one by one through the exit opening of said body for disposal on said seat, and resilient means interposed between said cover body and said seat-covers supporting means to urge the latter toward said forwarding means.

2. The device of claim 1, wherein the means passing through the cut of said central portion seat-covers and bearing on said seat-covers whereby to hold and guide the

10

15

20

same during exit of said seat-covers from said cover-body comprises a strong paper band.

3. The device of claim 1, wherein ears are rigidly secured to the closing wall of said cover body for receiving and supporting said forwarding means.
